UNITED STATES PATENT OFFICE.

JACOB HENDRICKSON, OF ROSSLAND, BRITISH COLUMBIA, CANADA, ASSIGNOR OF ONE-FIFTH TO ISAK W. JOHNSON, ONE-FIFTH TO ISAAC HENDRICKSON, AND ONE-FIFTH TO ALJOT HENDRICKSON, ALL OF ROSSLAND, BRITISH COLUMBIA, CANADA.

PERMUTATION-LOCK.

1,177,245.

Specification of Letters Patent. Patented Mar. 28, 1916.

Application filed June 3, 1915. Serial No. 31,953.

To all whom it may concern:

Be it known that I, JACOB HENDRICKSON, a citizen of the United States, residing at Rossland, in the Province of British Columbia and Dominion of Canada, have invented a new and useful Permutation-Lock, of which the following is a specification.

The present invention appertains to permutation locks, and aims to provide a novel 10 and improved lock of that nature adapted for use in safes, trunks, and the like.

It is the object of the invention to provide a permutation lock embodying improved features of construction and operation, whereby a number of successive operations are necessary to release the parts held together by the lock, to eliminate the possibility of any one without a knowledge of the combination opening the lock.

20 It is also within the scope of the invention to provide a permutation lock wherein a great many combinations may be had, that is, the device being adjustable in order that the numerals of the combination may be 25 changed a large number of times.

With the foregoing and other objects in view which will appear as the description proceeds, the invention resides in the combination and arrangement of parts and in the 30 details of construction hereinafter described and claimed, it being understood that changes in the precise embodiment of the invention herein disclosed can be made within the scope of what is claimed without departing from the spirit of the invention.

The invention is illustrated in the accompanying drawings, wherein:—

Figure 1 is a front view of a safe, trunk, or other receptacle illustrating the exposed 40 portions of the lock. Fig. 2 is an inside view of the lock in locked position. Fig. 3 is a sectional view of the lock, taken on the line 3—3 of Fig. 4, with the parts in released or open position. Figs. 4 and 5 are 45 sectional views, taken on the lines 4—4 and 5—5, respectively, of Fig. 2.

In the drawings, the numeral 1 designates a safe, trunk, or other receptacle having the hinged door 2 which carries the working 50 parts of the lock.

The lock embodies a tubular member 3 journaled through the door 2, and having a dial disk 4 upon its outer end and resting

against the outer side of the door 2. A spindle 5 is journaled through the tubular member 3 and has a dial disk 6 upon its outer end resting against the disk 4. The disks 4 and 6 are suitably graduated.

A tumbler disk 7 is mounted upon the inner end portion of the spindle 5 which projects beyond the inner end of the tubular member 3, and a tumbler disk 8 is mounted upon the tubular member 3 adjacent the door 2 or between the disk 7 and door. The tumbler disks are adapted to be rotated 60 upon the spindle 5 and tubular member 3 when the tumbler disks are released. The disks 7 and 8 are provided with marginal flanges 9 and 10, respectively, projecting toward one another and providing complementing or adjacent recesses 11 and 12, respectively.

As a means for adjustably holding the disk 7 upon the spindle 5, an arm 13 is slipped onto the inner end portion of the 75 spindle 5 and is so engaged to the spindle as to rotate therewith. A screw 14 is engaged through the arm or member 13 and is arranged to threadedly engage one of an annular series of threaded apertures 15 provided in the disk 7, whereby the disk 7 may be set at a large number of angular positions relative to the spindle 5.

As a means for adjustably holding the disk 8 upon the tubular member 3, a collar 16 is disposed non-rotatably upon the tubular member 3 between the disks 7 and 8, and a screw 17 is engaged through the collar 16 and is arranged to threadedly engage one of an annular series of threaded apertures 18 80 provided in the disk 8.

The flange 9 of the disk 7 is provided with a slot 19 which extends into the body of the disk 7, and the flange 10 of the disk 8 is provided with a notch 20.

As a means for supporting the inner end of the spindle 5 and holding the parts in place upon said spindle and tubular member 3, a bar 21 is hinged at one end, as at 22, to an inwardly projecting supporting member 23 attached to the door 2, and the bar 21 has an aperture 24 adjacent its free end through which the inner end of the spindle 5 is engageable when the bar 21 is swung into place. A cotter pin or other retaining element 25 is engageable with the inner end

of the spindle 5 for holding the bar 21 in place upon the said spindle. The bar 21 thus holds the arm 13 in place upon the spindle, and the arm 13 holds the disk 7 in 5 place, while the disk 7 holds the collar 16 upon the tubular member 3. The collar 16 holds the disk 8 in place.

When it is desired to change the combination, the cotter pin or retaining element 25 10 is removed, in which event, the bar 21 may be swung away from the spindle 5, and this allows the arm 13 and disk 7 to be drawn off of the spindle 5. The screw 17 is thus uncovered and may be released from the 15 disk 8, which allows the disk 8 to be adjusted relative to the collar 16. After the disk 8 is adjusted properly, the screw 17 is reapplied to the disk 8 by threading the screw into the proper aperture 18 of the 20 disk 8. The disk 7 and arm 13 are then replaced, and by loosening or removing the screw 14, the disk 7 may be adjusted relative to the arm 13 and spindle 5, so that the screw 14 in being reapplied will hold the 25 disk 7 in its new position with respect to the spindle. The bar 21 is then again swung into engagement with the spindle 5 for holding the parts thereon, and for also supporting the spindle properly.

30 The receptacle 1 carries a finger or keeper 26 which projects toward the tumbler disks 7 and 8 when the door 2 is closed, and the finger 26 has a head or knob 27 at its free end which is adapted to be received between 35 the tumbler disks within the flanges 9 and 10 thereof. The head 27 is movable through the slot 19 when the tumbler disks are properly arranged. Thus, when the tumbler disks are set so that the notches 19 and 20 40 aline with the finger 26, the head 27 of the finger 26 can move through the slot 19 when the door is closed or opened. When the head 27 is disposed between the tumbler disks and the tumbler disks are disarranged, 45 the head 27 will be locked within the flanges of the tumbler disks to prevent the parts from separating.

A pair of spindles 28 and 29 are journaled through the door 2 adjacent the tumbler disks, and have the respective knobs 30 and 31 secured upon their outer ends. Arms 32 and 33 are secured upon the spindles 28 and 29, respectively, upon the inner side of the door 2, and project to opposite sides of 50 the tumbler disks. The arms 32 and 33 have the angularly extending fingers 34 and 35 at their free ends, respectively, which fingers project toward the tumbler disks. The said fingers 34 and 35 have the heads 36 and 37, 55 respectively, adapted to pass through the slots 19 and 20 of the tumbler disks and to be engaged by the flanges of said disks. The fingers 34 and 35 are projectable through the respective openings 38 and 39 provided 60 in keepers 40 and 41 carried by the recep-

tacle 1 at opposite sides of the finger 26. The fingers 34 and 35 are arranged to pass through the openings 38 and 39, respectively, when the fingers 34 and 35 are swung into engagement with the tumbler disks. 70

The arm 33 has a portion 42 projecting therefrom, and the free end of the portion 42 is engageable with the arm 32 after the arm 32 has been swung into engagement with the tumbler disks, and when the arm 75 33 is swung into engagement with said disks, the arm 32 is held in engagement with the tumbler disks until the arm 33 is released.

When the door is locked, there are three 80 means for holding the door closed, and it requires a predetermined successive manipulation of a number of parts to liberate the door. When the door is closed, the fingers 26, 34 and 35 are projected or engaged between the tumbler disks. The fingers 26 85 being held between the tumbler disks will prevent the door from being opened, and the fingers 34 and 35 being engaged through the keepers 40 and 41, respectively, and being disposed between the tumbler disks, will also prevent the door from being opened. 90 This provides three distinct means for holding the door closed, and it is necessary to release the arm 33, arm 32 and finger 26 in 95 succession from the tumbler disks to open the door.

To open the door, the arm 33 is first released from the tumbler disks and keeper 41, this being accomplished by first properly 100 setting the dial disks 4 and 6 with respect to the pointer 43 provided upon the door 2, so that the notches 19 and 20 of the tumbler disks register with the finger 35 of said arm 33. The knob 31 is then turned in the proper direction to swing the arm 33 away from the tumbler disks, and this will retract the finger 35 from between the tumbler disks and out of the keeper 41. At the same 110 time, the projecting portions 42 of the arm 33 is swung out of engagement from the arm 32. Next, the dial disks 4 and 6 are properly adjusted to bring the slots 19 and 20 into alinement with the finger 34 of the arm 32, and the knob 30 is then swung 115 properly to swing the arm 32 away from the tumbler disks. This will retract the finger 34 from between the tumbler disks and out of the keeper 40. Now, the tumbler disks are again set to bring the notches 19 and 20 120 into alinement with the finger 26, and in which event, the finger 26 will move through the slot 19 to allow the door 2 to be swung open. It thus requires three adjustments of each of the two dial disks 4, or six adjustments in all and a proper manipulation of the knobs 30 and 31 to release the lock, and the arm 33, arm 32, and finger 26 must be released in succession from the tumbler 125 disks. As a result, the lock cannot be re- 130

leased without the combination being known, and the lock will serve its office in a thoroughly efficient and practical manner. The combination may be changed a large

5 number of times, as above indicated, and to lock the door closed, the operation above described is reversed, as will be apparent without further description being necessary. In other words, it is necessary to first engage 10 the finger 26 with the tumbler disks, and then the arms 32 and 33 in succession.

Having thus described the invention, what is claimed as new is:

1. In a device of the character described, 15 a member, a tubular member journaled therethrough, a spindle journaled through the tubular member, tumbler disks mounted upon the tubular member and spindle, a collar engaged non-rotatably upon the tu- 20 bular member between the tumbler disks, a securing element carried by the collar for engaging the tumbler disk which is mounted upon the tubular member, a member slipped upon the spindle, a securing element carried 25 by the last mentioned member to engage the tumbler disk which is mounted upon the spindle, the tumbler disks being rotatable upon the spindle and tubular member when they are released, and retaining means en- 30 gageable with the spindle for holding the parts upon the spindle and tubular member.

2. In a device of the character described, 35 a member, a tubular member journaled therethrough, a spindle journaled through the tubular member, tumbler disks mounted upon the tubular member and spindle, a collar engaged non-rotatably upon the tu- 40 bular member between the tumbler disks, a securing element engaged through the col- lar for engaging the tumbler disk which is mounted upon the tubular member, a member slipped upon the spindle, a securing element engageable through the last mentioned member to engage the tumbler disk 45 which is mounted upon the spindle, the tumbler disks being rotatable upon the spindle and tubular member when they are released, a member hinged to the first mentioned member and arranged to swing into engagement with the spindle, and means for holding 50 the last mentioned member in engagement with the spindle, said last mentioned member being arranged to hold the respective parts upon the spindle and tubular 55 member.

3. The combination with two parts movable to and from each other, of a pair of rotatable tumbler disks carried by one part and having marginal flanges projecting to- 60 ward one another and provided with notches, an oscillatory arm carried by said part and having an angularly extending finger at its free end provided with a head to pass through said notches to be engaged 65 by and released from said flanges, and a

keeper carried by the other part and having an opening through which said finger is movable when the finger is moved into engagement with the tumbler disks.

4. In a permutation lock, a manually operable rotatable tumbler disk, a manually operable movable member, and a manually operable second movable member, said members and tumbler disks having interengageable means whereby said members are held 70 by said disk until the disk is set to predetermined positions, and the second member having means engageable with the first mentioned member for holding the first mentioned member in engagement with the 80 tumbler disk until the second member is released.

5. In a permutation lock, a manually operable rotatable tumbler disk, and a pair of manually operable oscillatory arms, the free 85 ends of said arms and said disks having interengageable means whereby the disk holds the arms until the disk is set to predetermined positions, one arm having a portion to engage the other arm whereby the last 90 mentioned arm is held in engagement with the tumbler disk until the first mentioned arm is released.

6. In a permutation lock, a pair of rotatable tumbler disks having marginal flanges 95 projecting toward one another and provided with notches, and a pair of oscillatory arms having angularly extending fingers at their free ends provided with heads to move through said notches into and out of engagement with said flanges, one arm having a portion for engaging the other arm whereby the last mentioned arm is held in engagement with the tumbler disks until the first mentioned arm is released. 100

7. The combination with a receptacle having a door, of a tubular member journaled through the door, a spindle journaled through the tubular member, tumbler disks carried by the tubular member and spindle 110 at the inner side of the door, the tumbler disks having marginal flanges projecting toward one another, said flanges having notches and one notch extending into the body portion of the disk which is carried 115 by the spindle, a finger carried by the receptacle and having a head to pass through said notch when the door is opened and closed, said head being adapted to be held between the disks by said flanges, a pair of 120 spindles journaled through the door, arms carried by the last mentioned spindles at the inner side of the door, said arms having angularly extending fingers at their free ends, said angularly extending fingers having heads to move through said notches to be engaged by and released from said flanges, one arm having a portion to engage the other arm whereby the second mentioned arm is held in engagement with the tum- 125

bler disks until the first mentioned arm is released, and keepers carried by the receptacle and having openings through which the angularly extending fingers are movable when said fingers are engaged to the tumbler disks.

5 In testimony that I claim the foregoing

as my own, I have hereto affixed my signature in the presence of two witnesses.

JACOB HENDRICKSON.
